UNITED STATES PATENT OFFICE.

HENRY G. MILLER AND GEORGE R. LAWRENCE, OF CLEVELAND, OHIO.

ТИЛТИНГ СУППОРТ ФОР КАСКС.

No. 808,104.

Specification of Letters Patent.

Patented Dec. 26, 1905.

Application filed February 27, 1905. Serial No. 247,447.

To all whom it may concern:

Be it known that we, HENRY G. MILLER and GEORGE R. LAWRENCE, citizens of the United States, and residents of Cleveland, 5 county of Cuyahoga, and State of Ohio, have invented certain new and useful Improvements in Tilting Supports for Casks, of which the following is a specification, the principle of the invention being herein explained and 10 the best mode in which we have contemplated applying that principle, so as to distinguish it from other inventions.

The annexed drawings and the following description set forth in detail one mechanical form embodying the invention, such detail construction being but one of various mechanical forms in which the principle of the invention may be used.

In said annexed drawings, Figure I represents a side elevation of our improved tilting support for casks, and Fig. II an end elevation of the same.

This support is essentially devised for supporting casks under a racking device and thereupon tipping the filled and bunged cask onto inclined ways, down which it will roll to be further disposed of.

A rock-shaft 1 is journaled in suitable supports 2 and has two upwardly-extending 30 arms 3, formed with concave-curved heads 4, which form a cradle in which the cask rests. Said cross-heads project farther rearward than forward, and the lowermost point of the segmental curve of the cross-heads is to the 35 rear of the vertical plane of the rock-shaft, so that the cask resting in the cradle formed by the cross-heads will tend to tilt the same rearward. An arm 5 extends downward from the rock-shaft, and a pitman 6 is pivoted 40 to the end of this arm and to a piston 7 in a cylinder 8. This cylinder has a valve-chamber 9 at its closed end, which chamber has a port 10, leading into the cylinder, and an opposed port 11, communicating with an inlet-pipe 12 for air or other fluid under pressure 45 and also an exhaust-port 13 from the end of the cylinder. A valve 14 slides in the valve-chamber and has a circumferential groove 15, which connects the supply-port and inlet-port 50 when the valve is moved to one position and uncovers the exhaust-port to expose the same to the open end of the valve-chamber when the valve is moved to the opposite position. The valve has a stem 16, to which a lever 17 is pivoted, and said lever is fulcrumed at its opposite end and has a treadle 55

18, by means of which it may be depressed, and a spring 19, by which it is raised. Inclined rails 20 extend from points about in line with the cradle when in rest position to 60 the point of delivery for the filled casks.

In practice the cask is placed on the curved heads forming the cradle and is filled in the usual or any accepted manner. When the cask is filled and the bung has been driven to 65 close the cask, the operator depresses the treadle, which depresses the lever and the valve, placing the supply-port and inlet-port in communication. This admits motive fluid, such as compressed air, into the cylinder to drive the piston outward and tilting the cradle so as to swing the cask onto the rails, down which it then may run by gravity. When the treadle is released, the spring 70 raises the lever and valve, which latter uncovers the exhaust-port, so that the air may escape at the end of the valve-chamber. The cradle may now be returned to its upright position by placing a fresh cask in it, and the weight of the cask upon the long arms of the 75 cross-heads will return the cradle to its position of rest and force the piston in the cylinder back to exhaust the air from the latter. In this manner a cask may be supported to be filled and may easily and conveniently be 80 tipped and rolled from its support when filled.

Other modes of applying the principle of our invention may be employed for the mode herein explained. Change may therefore be 85 made as regards the mechanism thus disclosed, provided the principles of construction set forth, respectively, in the following claims are employed.

We therefore particularly point out and 90 distinctly claim as our invention—

1. The combination with inclined ways along which a cask may roll, of a rocking support in which a cask may rest and at a level with the upper end of said ways and having 95 its center of gravity in a plane to one side of the vertical plane of its fulcrum, a single-acting fluid-pressure cylinder, a piston in the same and connected to the support to rock the same, and means for admitting and 100 exhausting motive fluid into and out of the cylinder.

2. The combination with inclined ways along which a cask may roll, of a rocking support consisting of a rock-shaft having two 105 upwardly-projecting arms formed with segmentally-curved cross-heads at their upper

ends and said cross-heads having the lower-most point of their curve in a plane to the rear of the vertical plane of the rock-shaft, an arm projecting from the rock-shaft, a fluid-pressure cylinder, a piston in the same, a pitman pivoted to the piston and to the arm, a valve for controlling inlet and exhaust into and out of the cylinder, and a treadle connected to actuate said valve.

In testimony that we claim the foregoing to be our invention we have hereunto set our hands this 8th day of September, A. D. 1904.

HENRY G. MILLER.
GEORGE R. LAWRENCE.
